UNITED STATES PATENT OFFICE.

ARTHUR HAENICKE, OF BERLIN-TEMPELHOF, GERMANY.

MEANS FOR ATTACHING BUTTONS TO CARDS.

Application filed May 25, 1925, Serial No. 32,829, and in Germany May 30, 1924.

The invention relates to an article of manufacture comprising a plurality of buttons fastened to a card by means of a single thread stitched so that each button is fixed 5 in a safe and simple manner on the card, at the same time making it possible to detach each individual button without cutting the thread, for instance, for the purpose of selling a button from the card without detaching 10 or loosening the adjoining buttons.

A method for stitching buttons on cards by means of a thread is already known, however, the known methods have the disadvantage that for the purpose of detaching one 15 button the thread must be cut and that after detaching the one button the other buttons are loosened, so that they fall off from the card.

In the drawing is shown a button fastened 20 on a card, according to this invention:

Fig. 1 is a sectional detail partly in elevation showing how a loop is drawn through the first hole of a button fixed on a card.

Fig. 2 is a similar view showing how the 25 loop is taken off by a gripper in the downward movement of the needle.

Fig. 3 is a similar view showing the needle in a position in which it is to be inserted in the second hole of the button, while the 30 gripper holds the loop.

Fig. 4 is a similar view showing the formation of the loop in the second hole of the button.

Fig. 5 is a similar view showing the introduction of the first loop into the second loop by the gripper, while the needle moves downward.

Fig. 6 is a similar view showing how the first loop is impressed by the second loop 40 while the gripper moves backward and shortly before the needle is pulled out, and

Fig. 7 is a similar view showing an already fixed button and the needle in a position in which it is ready to fasten a second button upon the card.

The needle "1" pulls the thread "2", (as shown in Figure 1) from below through the card "3" and one button hole of the button "8" which is to be attached. In Figure 2 50 the needle goes again downwards and in doing so the thread "2" forms, right and left of the needle, a loop. Now, the gripper "5" catches the loop "6" which is formed by the end of the thread running from the needle.

Figure 3 shows the needle "1" after it has 55 been pulled out entirely and after it has

moved to the side and to the point where the second penetration shall be made. This second stitch is formed in Figure 4. When the needle "1", as shown in Figure 5, moves 60 downward again loops are again formed, and the gripper "5" shifts the loop "6" which has been held back before, through the loop "7" which is formed by the end of the thread running from the needle. 65

The gripper "5" is drawn back during the second downward movement of the needle "1" so that the loop "7" tightly surrounds the loop "6" as it is shown in Figure 6.

In the further downward movement of the needle the loop "7" pulls the loop "6" into the hole of the button, so that in this hole six thicknesses of the thread are present and the outer end of the loop "6" is held fast by the strong friction of the various thread parts within the button hole. Hereafter, the card is further moved by the distance of a button and the process of stitching is repeated. 75

Figure 7 shows how the loop "6" is drawn 80 into the button hole by the loop "7" and how the card has been already moved by the distance of the buttons in order to begin with the fastening of the next button "9".

Having thus fully described the invention, 85 what is claimed as new and desired to be secured by Letters Patent is:—

1. As an article of manufacture, a plurality of buttons attached to a card by means of a single thread each button being singly 90 detachable and attached by a stitch consisting of a pair of single loops passing through two holes in each button, the first loop passing over the button from the one hole to the other and being drawn through the second loop and pulled into the second hole thus having in this hole six thicknesses of thread. 95

2. As an article of manufacture, a plurality of buttons attached to a card by means of a single thread, each button being singly 100 detachable and attached to the card by a stitch consisting of a pair of single loops passing through two holes in each button, the first loop passing over the button from the one hole to the other and being drawn through the second loop and pulled into the second hole and pressed upon the card thus having in the second hole six thicknesses of thread. 105

In testimony whereof I have signed my 110 name to this specification.

ARTHUR HAENICKE.
